ATTORNEYS

UNITED STATES PATENT OFFICE.

HENRY WATERS, OF BISBEE, ARIZONA.

SHOE-STRETCHER.

1,340,994.

Specification of Letters Patent. Patented May 25, 1920.

Application filed September 25, 1919. Serial No. 326,153.

To all whom it may concern:

Be it known that I, HENRY WATERS, a citizen of the United States, and a resident of Bisbee, in the county of Cochise and State of Arizona, have invented certain new and useful Improvements in Shoe-Stretchers, of which the following is a specification.

This invention is an improvement in shoe stretchers, and has for its object to provide a device of the character specified, by means of which the shoe may be stretched in many directions either longitudinally or laterally at different points or 15 in a vertical direction.

In the drawings:—

Figure 1 is a side view of the improved stretcher;

Fig. 2 is a view, looking at the inner side 20 of one of the sections of the stretcher;

Fig. 3 is an end view, looking at the rear or heel portion of the stretcher;

Fig. 4 is a plan view of the stretcher plate;

Fig. 5 is a section on line 5—5 of Fig. 25 4; and

Fig. 6 is an end view of the vertical stretcher.

In the present embodiment of the invention the improved stretcher comprises a pair of similar sections 1, shaped to fit within the shoe to be stretched and the sections are connected at the rear or heel end by means of the hinge shown more particularly in Fig. 3. This hinge comprises pairs of hinged leaves 2 and 3, a pair being secured to each section of the stretcher and the leaves are similar. The leaf 2 of each pair carries a bearing 4, which is adapted to aline with the bearing 5 of the other member of the pair, and with the bearings 4 and 5 of the other pair, to receive a pintle pin 6. This pintle pin as shown is of greater length than the aggregate distance between the outer faces of the outermost bearing so that the pairs of leaves may move away from each other during the operation of stretching, and the ends of the pintle pin are headed, as shown, to limit this spreading movement of the pairs.

Each section of the stretcher is grooved

on its inner face, as indicated at 7, the groove extending from the heel to the toe and the grooves are in register when the sections are properly connected. At the heel 55 end of each groove 7 an opening 8 is provided extending outwardly through the section, and each opening is adapted to receive one end of a cross head 9 on the nut 10, which is arranged between the section. A 60 screw-threaded rod 11 is threaded through the nut, and this rod, as shown, more particularly in Fig. 1, has its ends threaded in opposite directions, one of the said threaded ends engaging the nut. The other end of 65 the rod passes through a nut 12, and is provided with a handle 13 beyond the nut.

The stretcher plate 4, shown in Fig. 4, is detachably connected with the inner end of the rod 11. This plate as shown is a 70 split loop having rounded side edges and having the split at the rear or heel end of the plate. The side walls of the split are rounded to permit the passage of a neck at the end of the rod, the said rod having a 75 head beyond the neck which is adapted to engage within an opening of the plate and means is provided for engaging the head to prevent the withdrawal of the rod, the said means being releasable. In the present instance the means is a split ring 15, which is 80 threaded into the central opening of the plate between the corners of the split and a projection 16 which extends into the central opening of the plate. The split of this 85 split ring is adapted to register with the split of the plate 14 to disengage the head of the rod, or to move out of register with the split of the plate to hold the rod from rearward movement with respect to the 90 plate. Thus the split ring 15 detachably connects the rod 11 to the plate 14.

Referring to Fig. 2, it will be noticed that the grooves 7 of the sections have inward portions, indicated at 17, which are in register in the two sections, to receive the plate 14, to permit the sections to abut or to approximately abut. The bottom wall of the groove inclines from each depression 17, so that when the plate is moved longitudinally 100 of the groove out of the depression the same will be spaced apart. One of these depres-

sions is near the heel end, while the other one is nearer the toe end. When the plate 14 is in the heel depression 7 the body of the shoe, namely that portion near the in-
5 step, will be stretched when the stretcher is expanded, while when the plate 14 is near the toe, the toe will be stretched while the toe of the stretcher is stretched.

A frame 18 is provided for coöperating
10 with the stretcher 1 to stretch the shoe longitudinally. The plate 18 has a vertical slot forming a guide-way, in which the nut 12 is received and it will be noticed, referring to Fig. 2, that the nut has grooves 19 extending longitudinally thereof, but inclined with respect to the nut for receiving the side walls of the slot of the frame. Thus when the nut is in place in the frame, as shown in Fig. 2, the frame will be almost thereagainst.
15 20 This frame has an enlarged portion 20 at its lower end forming a head for engaging within the heel of the shoe and the said head may be covered with leather or the like, as shown, to prevent injury to the in-
25 terior of the shoe.

In order to provide for vertical stretching, the attachment shown in Fig. 6 is used. This attachment comprises plates 21 and 22 arranged with their planes substantially
30 parallel and connected by a vertical plate 23 arranged at the center of the plates 21 and 22. The plate 22 is shaped to fit within the groove 17 between the sections, with the plate 23 passing through the space between the section, to hold the plate 21 above the level of the top of the stretcher, as shown.

Referring to Fig. 2, it will be noticed that the groove 7 is more nearly horizontal
40 than the upper surface of the sections 1, so that this groove is farther from the top of the section toward the heel than at the toe. Hence when the plate 22 is moved forwardly with respect to the stretcher, the plate 21 will be moved farther above the stretcher, thus increasing the distance between the top of this plate and the bottom of the stretcher. Hence the shoe may be stretched in a vertical direction. It will be
45 understood that the usual plates indicated at 24 may be connected with the stretcher at any desired point for stretching particular parts of the shoe, as for instance at the location of bunions.

50 55 In operation, the stretcher is introduced into the shoe with the plate 14 in that set of depressions 17 where it is desired to stretch the shoe either at the ball of the foot or at the toe. When in place, if it is desired to stretch the shoe laterally the plate is moved longitudinally of the shoe. This moves the sections apart and stretches the shoe at the point desired. If it is desired to stretch the shoe longitudinally, the element

20 of the frame 18 is engaged in the heel 65 and the plate 14 may be removed. When now the rod 11 is turned it will be evident that the frame and stretcher will be moved in opposite directions to stretch the shoe longitudinally. To stretch the shoe vertically, the attachment shown in Fig. 6 is placed as shown in Fig. 1, and it may be moved longitudinally of the shoe by means of the rod.

I claim:—

1. A shoe stretcher comprising similar sections grooved on their inner faces, the grooves registering, said sections being slidably connected at the heel end, each groove having depressions in its bottom at the ball 80 and at the toe spaced apart from each other and registering with those of the other sections, a stretcher plate, a nut journaled between the sections, a rod threaded through the nut for moving the stretcher plate, said 85 rod having its ends threaded in opposite directions, a heel engaging frame, and a nut on the rear end of the rod with which the frame is slidably connected to permit the shoe to be stretched longitudinally. 90

2. A shoe stretcher comprising similar sections, grooved on their inner faces, the grooves registering, said sections being slidably connected at the heel end, each groove having depressions in its bottom at the ball 95 and at the toe spaced from each other and registering with those of the other sections, a stretcher plate, a nut journaled between the sections, a rod threaded through the nut for moving the stretcher plate and a detachable connection between the stretcher plate and the rod, and an attachment for vertical stretching comprising a plate movable in the grooves in the place of the stretcher plate or in front of the same, said plate having a 100 second plate arranged above the same and connected therewith, the connection extending through the space between the stretcher sections.

3. A shoe stretcher comprising similar 110 sections, grooved on their inner faces, the grooves registering, said sections being slidably connected at the heel end, each groove having depressions in its bottom at the ball and at the toe spaced from each other and 115 registering with those of other sections, a stretcher plate, a nut journaled between the sections, a rod threaded to the nut for moving the stretcher plate, and a detachable connection between the stretcher plate and the 120 rod.

4. A shoe stretcher comprising similar sections grooved on their inner faces, the grooves registering, said sections being slidably connected at the heel end, each groove 125 having depressions in its bottom at the ball and at the toe spaced apart from each other and registering with those of the other sec-

tions, a stretcher plate, a nut journaled between the sections, and a rod threaded to the nut for moving the stretcher plate.

5. A shoe stretcher comprising similar sections grooved on their inner faces, the grooves registering, and each groove having depressions in its bottom at the ball and at the toe spaced apart from each other and

registering with those of the other section, a stretcher plate, and means for operating 10 said plate to move it longitudinally of the stretcher, said plate being received in the depressions during the insertion of the stretcher in the shoe.

HENRY WATERS.
